WRENCH HAVING SPRING-PRESSED SHOE FOR SLIDABLE AND ROCKABLE JAW

Henry St. Pierre, Worcester, Mass.

Application August 22, 1955, Serial No. 529,769

10 Claims. (Cl. 81—101)

This invention relates to a new and improved wrench construction which is particularly adapted to Stillson type or pipe wrenches wherein there is an elongated shank having a jaw thereon and a relatively movable shank also having a jaw, for cooperation with the jaw on the elongated shank, such wrenches usually including a nut or the like for advancing the movable shank relative to the elongated shank, and the movable shank having a rocking motion relative to the elongated shank on an axis at right angles to the relative direction of motion thereof, as is well known in the art, and the present invention has for its principal object the provision of improved and increased rocking action, making the same "live" rather than "slow," and including novel resilient means for normally maintaining the movable shank in a "neutral" position, said movable shank being capable of the rocking motion in either direction, so that the jaw on the movable shank may be moved away from the jaw on the elongated shank, and may also be moved toward the same for increased gripping action on an object such as a pipe or the like in the jaws; the provision of resilient means as aforesaid including a shoe or the like on which the movable shank may slide, said shoe being provided with a pair of oppositely extending feet portions, each of which contacts the end of a spring, so that when the movable shank is rocked in either direction, it compresses a spring depending upon the direction of rocking motion and this provides for an increased angle of rock or increasing rocking motion, so that the wrench grips better than like wrenches of the prior art.

Other objects of the invention include the provision of a new and improved spring holder held in a novel manner within the main body of the elongated shank portion of the wrench, and in the relationship of the shoe and the feet thereon above described with the spring or springs in the spring holder, and with certain portions of the spring holder, whereby upon rocking action of the movable shank both ends of the spring or springs are compressed but to different degrees so as to increase the resiliency and "live" feel of the rocking action.

Other objects and advantages of the invention will appear hereinafter.

Reference is to be had to the accompanying drawings, in which:

Fig. 1 is an elevation with parts broken away and in section illustrating a form of the invention and showing the movable shank in neutral or intermediate position;

Fig. 2 is a similar view showing the movable shank in its extreme position wherein the jaws are separated;

Fig. 3 is a similar view showing the parts in their closest position for the particular wrench adjustment;

Fig. 4 is an enlarged view illustrating a modification of the spring construction;

Fig. 5 is an enlarged section on line 5—5 of Fig. 1;

Figs. 6 and 7 illustrate further variations of the spring construction; and

Figs. 8 and 9 are diagrammatic views, respectively, of the variations shown in Figs. 6 and 7, and further illus-

2

trating the compression of the springs during use of the wrench.

Referring to Figs. 1, 2 and 3, the numeral 10 generally indicates the elongated shank of a wrench which is provided with a spur at 12 for slidably guiding a movable shank 14. The elongated shank 10 is provided with a projection 16 having a through aperture 18 therein for receiving the movable shank 14 slidingly in parallel relation to the shank 10, and a nut 20 is used for cooperation with screw-threads 22 for adjusting the movable shank 14 relative to the elongated shank 10. Both shanks are provided with jaws as at 24, 26, all as well known in the art.

The through aperture 18 has opening into the same a deep notch or aperture indicated at 28, this notch being located centrally of the shank 10 and intersecting the through aperture 18. The notch 28 is provided at each end with an overhanging shoulder 30 which serves to hold in place in the notch a spring holder. As shown in Figs. 1 to 4 inclusive, this holder is of a general W shape, and it is provided with lateral side runs 32, 34, shorter connecting bottom runs 36, 38, the longer side runs 32 and 34 terminating in in-turned feet 40, 42.

The longer side runs 32, 34 are arranged at an angle to each other and the shorter bottom runs 36, 38 provide for locating means substantially at right angles thereto providing reaction surfaces for a pair of coil springs 44, 46.

These springs find their opposite reaction point against the inclined feet 48, 50 which are the terminal portions bent downwardly as shown from a central bridge member 52 welded or otherwise secured to a concave, convex elongated shoe 54. This shoe 54 forms a sliding support for the lower edge of the movable shank 14, the latter having convex edges, as is usually the case, and the lower edge fitting the concavity as shown in Fig. 5.

It will be seen that the springs, holder, and shoe all form a unit as shown in Fig. 4 which is insertable into the notch 28 by squeezing the ends of the runs 32 and 34 and dropping the unit laterally into the notch 28 from the through aperture 18. Then, upon depressing shoe 54 against the action of the springs 44, 46, the movable shank 14 may be inserted as will be clear to those skilled in the art.

Referring now to Fig. 2, there is here shown the action of the novel device when the same is actuated in order to provide a wide gap between the jaws of the wrench for the reception of an object to be clamped therebetween. In this case, the end edge of the through aperture 18 which is indicated at 56 forms a fulcrum for the movable shank 14 which rocks down away from the top edge 58 and aperture 18. This action causes shoe 48 to move down away from in-turned end 40 of the spring holder, thus compressing spring 44. At the same time, the foot 50 is moved slightly down away from its corresponding in-turned end portion 42 of the side run 34 of the spring holder and this also tends to compress the spring 46, so that the resilient pressure exerted on the shank 14 tending to move it back into the intermediate or neutral position of Fig. 1 is considerably increased. Although the position of the parts shown in Fig. 2 is easily achieved manually, a greater range of action of the movable shank in rocking is obtainable by reason of the increased resilient tension which is applied to the springs.

When the wrench is then turned to grasp the object between the jaws, the opposite action takes effect as shown in Fig. 3 and in this case the spring 46 is compressed to a relatively high degree when the spring 44 is compressed to a lesser degree. In either case, the foot 48 or 50 which performs the smaller tensioning of the spring, finds its fulcrum at its end adjacent the run 32 or 34 of the spring holder, at the juncture thereof with the respective in-turned portion 40 or 42. Whereas in neutral position the ends of the shoes 48, 50 are spaced from their respective spring holder side runs 32,

34, these feet slide slightly sidewise to find the fulcrum points described above and plainly illustrated in Figs. 2 and 3.

Referring now to Figs. 6 and 8, there is here shown a modification of the device wherein the spring holder is indicated generally at 60 and it is of arc shape having its ends turned in at 62, 64 and overlying the terminal portions of the feet 66, 68 respectively. These feet extend downwardly at an angle from the shoe 70 which is comparable to that at 54. In this case, there is a single spring 72, the ends of which are engaged by the feet 66 and 68 but the action of this spring, as illustrated in Fig. 8, is substantially the same as above described with respect to the form of the device shown in Fig. 4.

Figs. 7 and 9 show another form of the device where the spring holder generally indicated at 74 is of box form having a straight bottom portion, straight sides 76, 78 and directly in-turned ends 80 and 82 overlying the feet 84 and 86 which are a part of the shoe 88, again comparable to that at 54. In this case, there are two springs which are similar to those at 44 and 46 and these are indicated at 90 and 92. One action of this form of the invention is illustrated in Fig. 9 and it will be seen to be substantially the same as the form illustrated in Fig. 4.

It will be seen that this invention provides a relatively simple, easily assembled, spring construction which is completely housed within the parts of the wrench so that there are no protruding spring members, and the construction of the device is such as to provide for a greatly increased range of rocking action of the movable shank and also it provides for a positive resilient force impressed upon the movable shank in either direction, so that the shank is not merely allowed to move because of the absence of sufficient spring means to move it, but it is positively actuated in either direction as above described.

Having thus described my invention and the advantages thereof, I do not wish to be limited to the details herein disclosed, otherwise than as set forth in the claims, but what I claim is:

1. A wrench comprising a handle, a fixed gripping jaw thereon, a shank, a jaw on the shank, the latter being movable with respect to the handle and the fixed jaw, means on the handle forming a passage for receiving and loosely guiding the shank, a spring device in the passage, said device bearing on the shank and maintaining the same between two extreme positions of motion in a direction transverse to the line of movement of the movable jaw, said spring device comprising a rockable shoe slidably engaged by the shank, means to hold the shoe against sliding in the passage, a pair of spaced feet on the shoe, spring means engaged by both feet for compression of the spring means by the rocking action of the shank and shoe in either direction, the spring means comprising a single coil spring transversely deformed to engage a foot at each end of the spring.

2. A wrench comprising a frame having a fixed jaw, an apertured projection associated with the frame, a recess within the projection and intersecting the aperture, a movable jaw, a shank thereon, said shank being located in the aperture, a spring device in the recess bearing on the shank and yieldably holding the same in an intermediate inactive rockable position relative to the frame, said spring device comprising a rockable shoe slidably relative to the shank, means loosely holding the shoe in

the recess against sliding, spring means urging the shoe into contact with the shank, a foot at each end of the shoe engaging the spring means, and a spring holder embracing the spring means and having ends contacting the feet and acting as stops and fulcrums therefor.

3. A wrench comprising a frame having a fixed jaw, an apertured projection associated with the frame, a recess within the projection and intersecting the aperture, a movable jaw, a shank thereon, said shank being located in the aperture, a spring device in the recess bearing on the shank and yieldably holding the same in an intermediate inactive rockable position relative to the frame, said shank being threaded, a nut engaged with the shank to move it rectilinearly, said spring device comprising a spring holder having inturned ends, a spring means in the holder, a shoe engaging the shank, a pair of spaced feet on the shoe located under the inturned ends of the holder and yieldingly held thereto by the spring means, the latter compressively engaging the feet.

4. The wrench of claim 3 wherein the spring holder is generally V-shaped and the spring means comprises a transversely bent spring conforming to the V, the in-turned ends of the holder forming the free ends of the V.

5. The wrench of claim 3 wherein the spring holder being of general U-shape and the spring means comprising a pair of springs, one at each side of the U, and within the same.

6. The wrench of claim 3 wherein the spring holder being of general U-shape and the spring means comprising a pair of springs, one at each side of the U, and within the same, said springs being parallel.

7. The wrench of claim 3 wherein the spring holder being of general U-shape and the spring means comprising a pair of springs, one at each side of the U, and within the same, said springs being angularly inclined relative to each other and the arms of the U being likewise inclined.

8. A wrench comprising a frame, a fixed jaw thereon, a movable shank loosely held to the frame, a jaw on the shank, a spring device contacting the shank and yieldingly holding the same in a substantially central position in the frame so that the shank is rockable in either direction, said spring device comprising a holder including a pair of arms having inturned ends, a shoe engaging the shank, a foot adjacent each end of the shoe and spaced therefrom, each foot being engaged under a respective inturned end on the spring holder and rockably associated therewith with the extreme end of each foot finding a fulcrum on its inturned end, and spring means yieldingly holding each foot to its said inturned end.

9. The wrench of claim 8 including means in the frame engaging the inturned ends of the spring holder at the sides thereof opposite the spring means, and holding the spring holder in the frame.

10. The wrench of claim 8 including means in the frame engaging the inturned ends of the spring holder at the sides thereof opposite the spring means, and holding the spring holder in the frame, said spring holder being resilient and snapped in under the means holding the same.
